ELECTRICAL CONNECTION

Edgar S. Stem, Alderson, Pa., assignor of one-half
to Albert A. Stull, Alderson, Pa.Application June 22, 1928, Serial No. 287,606
Renewed May 10, 1935

5 Claims. (Cl. 173—343)

This invention relates to electrical connections and more particularly to electrical connections including a part having contact tangs extending therefrom in the same direction and a tang-receiving part having contact springs to be engaged by said tangs when inserted into the second part.

The tang-bearing and tang-receiving parts of such connections are frequently pulled apart in use, thus causing inconvenience and annoyance. An important object of the invention is to provide devices of the kind specified which will be substantially free from such difficulties and at the same time be so constructed and arranged as to be separated easily when it is desired to do so.

Another object of the invention is to provide connecting devices including a member having tangs extending in the same direction therefrom, at least one of said tangs having a rearwardly facing shoulder, and a tang-receiving member having a catch adapted to engage said shoulder upon insertion of the tangs and cooperate with said shoulder to prevent accidental withdrawal of the tangs, the construction and arrangement being such that by a slight relative movement, as, for example, rotation of the two members, in a direction transverse to the tang, the locking engagement between the tang and the catch or locking device will be broken, thus enabling ready separation of the tang-carrying and tang-receiving members.

Although for illustrative purposes, an arrangement in the form of a plug with a tang-receiving portion adapted to be screwed into a screw-socket and a tank-carrying portion adapted for use with the tang-receiving portion, is shown and described; it should be understood that the tang-receiving portion of the connection may be of other forms, for example, an electrical outlet in a wall or the like.

A further feature of the invention resides in the provision of tang-locking and controlling devices which may be used with ordinary tangs which would not cooperate therewith for locking purposes, as well as with tangs adapted to cooperate with such locking devices.

It should also be understood that the locking or latching devices may be associated with the contact springs of the tang-receiving parts of the electrical connections and may be integral therewith or separate therefrom.

Other features and advantages will appear upon consideration of the following description and the drawing, in which:

Fig. 1 is a view in elevation of a connection illustrating a satisfactory embodiment of the present invention, part of the structure being broken away to show the locking device at the farther side;

Fig. 2 is a view of a connection in which the tang-carrying part is shown in central section

and gives a view of the locking devices in a direction at right angles to the line of view in Fig. 1;

Fig. 3 is a sectional plan view taken along the line 3—3 of Fig. 1;

Fig. 4 is a view illustrating a combined contact spring and locking device in which the parts are integral with each other; and

Fig. 5 is a view similar to Fig. 3 but with the locking and controlling device proper separate from the contact spring.

Referring to the drawing, 10 designates an electrical connection or plug including a part or cap 11 from which tangs or contacts 12 project in the same direction, and a tang-receiving part or base 13 including contact members in the form of leaf springs 14 and 15 and having their outer ends turned out of alignment sufficiently to assure engagement thereof by said tangs 12 for pushing the leaf springs to one side and maintaining effective contact therewith. Preferably the body of the cap 11 is of insulating material and the tangs which are substantially parallel are connected therewith at one end and also to conductors in a cord 15a which extends centrally through the cap at its outer side. The tangs 12 are substantially the same as those in general use but each of them is provided with a recess or notch 16 for a purpose to be brought out more clearly hereinafter.

The base 13 consists of a body of insulating material having openings 17 and 18 therethrough to receive respectively the leaf springs or contacts 14 and 15. The leaf spring 14 is connected at the lower end of the base with a screw-threaded shell 19 surrounding the base and adapted to be screwed into a suitable socket. The end of the base 13 adjacent the screw-threaded shell 19 is covered by a plate 20 of insulating material having at its center a perforation to receive a metallic member 21 secured in the base 13 and extending axially therefrom. The contact or leaf spring 15 extends through an opening in the plate 20 and an offset 22 from the spring 15 at the outer side of the plate 20 is provided with a perforation 23, as shown in Fig. 4, to receive the member 21.

The plate 20 of insulating material and the contact spring 15 are held in proper relation to the body of the base 13 by placing a spring member or washer 24 over the outer end of the member 21 and upsetting the outer end of said member 21 so as to press the spring member 24 against the offset 22 of the contact 15, the offset 22 in turn engaging the outer face of the insulating member 20 and holding it against the body of the base 13.

The structure thus far described is in general the same as for plugs heretofore in use. In the illustrative embodiment of the invention, tang-locking devices are provided in connection with each of said spring contacts 14 and 15. These locking devices may be substantially the same for

both contacts and it will therefore be sufficient to describe the locking device associated with the contact spring 15.

One form of combined contact spring 15 with the locking device or devices is shown in Fig. 4.

- 5 The actual locking is done by means of a leaf spring 25 extending upwardly from the offset or base 22 of the contact and having its upper end directed inwardly to form a hook 26 adapted to enter the notch 16 of a tang 12 when the cap 11 and base 13 are pressed together. In this connection it should be noted that the upper surface of the hook curves downwardly so that when engaged by the rounded lower edge of a tang 12 it may be forced back and held in such condition 10 until a recess or notch 16 is brought into position to permit the hook 26 to enter the same.

In order to assure proper positioning of the hook 26 for engagement by a tang during insertion, a portion of the spring contact 15 adjacent to the spring 25 may be utilized to limit the forward movement of the spring 25 and hook 26. As here shown, the stop portion of the spring contact 15 is in the form of a lug or stop 27 at the edge of the contact and substantially perpendicular to the flat portion of the spring contact. To assure proper guiding of the tang 12 to be brought into engagement with the spring contact 15 the offset or base 22 is provided at its edge opposite the spring 25 with another leaf spring 28 directed outwardly at its upper end so as to facilitate the insertion of the end of the tang. This leaf spring 28 not only assures proper cooperation of an inserted tang with the hook 26 but also permits movement of the tang away from the hook 26, by relative rotation of the tang bearing member and the tang receiving member about an axis substantially parallel to the tangs to effect unlocking of the tang and the hook so that the cap 11 and the base 13 may be separated.

- 40 As shown in Fig. 4 the springs or locking members 25 and 28 are integral with the spring 15. In some cases, however, it may be desirable to have the springs 25 and 28, constituting the principal parts of the locking device, separate from the spring 15. As shown in Fig. 5, this result is obtained by forming the springs 25 and 28 of a single piece including a connecting portion 29 to be placed beneath the offset 22 of the spring 15. In this arrangement of the spring 15 and locking members 25 and 28, the forward movement of the member 25 may be limited, as in Fig. 4, by a lug 27 projecting from one edge of the contact spring 15.

The proper relative positions of the contact and locking and controlling device shown in Fig. 5, may be maintained in any suitable manner.

It will be evident that, although the locking devices are designed to cooperate with suitable tangs, the base 13 is fully adapted for use with tangs which have no special formation to cooperate with the locking devices.

It should be understood that various changes may be made in the construction and arrangement of the parts and that certain parts may be used without others, without departing from the true spirit and scope of the invention.

Having thus described my invention, I claim:

1. An electrical connection device adapted to receive parallel contact tangs on another connection device, including contact springs to be engaged by said tangs, and means for interlock-

ing said connection devices, including a separate spring latch adjacent and movable with respect to one of the contact springs in the tang-receiving device, and adapted to engage a recess in a tang when thrust into engagement with such spring, the arrangement being such that the interlocking means will be released upon a slight relative rotation of said contact devices about an axis parallel to and midway between said tangs. 5

2. A device for use in an electrical connection part adapted to receive contact tangs projecting in the same direction from another part, including a leaf spring contact shaped at one end to be engaged by the forward end of a tang and pressed to one side as the tang is moved therewith, a latching device including a leaf spring arranged to act across the face of said leaf spring contact and having a projection adapted to engage a rearwardly facing shoulder at the edge of a tang inserted along said leaf spring contact, 15 and a leaf spring adjacent to the opposite edge of said leaf spring contact adapted to press a tang toward the leaf spring of the latching device so that when the tang reaches the proper position, said adjacent leaf spring will enable the projection to engage over said shoulder, and yield to enable lateral separation of said latch and shoulder in a direction across said leaf spring contact. 25

3. An electrical connection including a cap 30 with contact tangs projecting therefrom in the same direction and each having a rearwardly facing shoulder at one edge thereof, a tang-receiving part having main parallel leaf spring contacts to be engaged by said tangs, and means 35 normally effective for preventing separation of said cap and tang-receiving part including a latch in the form of a leaf spring adjacent to one edge of one of said contact springs and shaped to enable a tang to be inserted along the adjacent spring contact and then to engage the shoulder on the tang, and a guiding spring to direct such tang into proper position along the contact but permitting lateral movement of the tang to release it from the latch. 40

4. In an electrical connection, a leaf spring contact arranged for engagement by a contact tang, a leaf spring at one edge of said contact and having a hooked upper end serving as a latch to engage a shoulder at the edge of said tang, a stop on said contact to limit the forward movement of the latch spring, and a leaf spring at the other edge of the contact spring with an outwardly directed upper end and acting to guide the tang into operative engagement with said latch while permitting lateral movement of the tang to release it from the latch. 45

5. In an electrical connection, a leaf spring contact arranged for engagement by a contact tang, a leaf spring at one edge of said contact and having a hooked upper end serving as a latch to engage a shoulder at the edge of said tang, a stop on said contact to limit the forward movement of the latch spring, and a leaf spring at the other edge of the contact spring with an outwardly directed upper end and acting to guide the tang into operative engagement with said latch while permitting lateral movement of the tang to release it from the latch, the latch spring and the guiding spring being integral at their inner ends. 60
